UNITED STATES PATENT OFFICE.

DANIEL L. BRAINE, OF NEW YORK, N. Y., ASSIGNOR, BY MESNE ASSIGNMENTS, TO COMPOSITE TIE-PLATE CORPORATION, OF NEW YORK, N. Y., A CORPORATION OF NEW YORK.

RAIL SUPPORTING AND FASTENING DEVICE.

1,083,270.

Specification of Letters Patent.

Patented Jan. 6, 1914.

Application filed March 15, 1913, Serial No. 754,501. Renewed November 21, 1913. Serial No. 802,327.

To all whom it may concern:

Be it known that I, DANIEL L. BRAINE, a citizen of the United States, residing at New York city, in the county of New York and State of New York, have invented certain new and useful Improvements in Rail Supporting and Fastening Devices, of which the following is a specification.

This invention relates to improvements in rail supporting and fastening devices, and has for its object: to provide an improved form of supporting and securing means for holding a rail in place.

Another object is to provide means for firmly securing the rail as the supporting member wears down.

Another object is to provide a construction which will strengthen or reinforce the fastening members against outward bending as a result of stress, or thrust, imparted to them by the base of a rail.

Still another object is to provide an improved form of screw spike, which will permit secure retaining of the rail in place as the same wears down the supporting block.

In connection with the construction shown and described in for example, the co-pending application, No. 727,535, filed October 24, 1912, I have found it advisable to provide a fastening means which will permit ready removal of the rail, without requiring entire withdrawal of the screw spike. I have also found it advisable, in order to comply with some conditions often met with in railroad practice, to provide for the following down of the rail base, as the latter wears into the supporting block.

These and other objects will be set forth in the following specification and accompanying drawings, in which—

Figure 1 is a side elevation of my device. Fig. 2 is a plan view of the same, showing one of the spikes removed. Fig. 3 is an end elevation of the same. Fig. 4 is a detail cross-section, showing a spike in elevation. Fig. 5 is a view similar to Fig. 4, showing the spike in a different position, after the rail has worn the block down some distance. Fig. 6 is a perspective of one of my screw spike heads. Fig. 7 is a perspective of the metal frame; and Fig. 8 is a perspective of the supporting block.

Like numerals refer to like elements throughout the drawings, in which—10

designates a conventional form of rail having flanged base, 11. 12 indicates the usual form of railway tie, upon which is located supporting block 13, of substantially rectangular cross-section, which may have the bolting apertures 14 there-through, as shown in Fig. 8.

The metal frame, 15, having the top portions, 15^a, 15^b, and sides 15^c, 15^d, is adapted to rest on and closely fit the block 13, as shown. The top portions, 15^a, 15^b, are spaced apart a distance approximately equal to the width of the rail base, 11, the latter being adapted to be seated there-between, as shown in Fig. 2, for example. The sides 15^c, 15^d, of the frame 15, are cut away between the top portions 15^a and 15^b, as shown in Fig. 7, and are constructed preferably to terminate short of the upper surface of the tie, 12, when in position as shown in Fig. 3, thereby eliminating the possibility of the crushing or bruising of the tie by the frame, 15. This construction in general is similar to that shown and described in the above-mentioned co-pending application.

The top portions 15^a, 15^b, of the frame, 15, are provided with the spiking apertures or slots, 16, opening into the space between the top portions, as shown in Fig. 7. A portion of the metal frame around each of the apertures, 16, is dished out, or cut away, to form a helical surface, as indicated by numeral 16^a. These inclined portions, 16^a, commence flush with the surface of the corresponding top portion, at a point approximately half-way around the spiking aperture 16—in other words, on a line drawn parallel to the sides 15^c, 15^d, through the center of the spiking aperture, 16. These inclined surfaces incline downwardly from the point described to approximately the under side of the corresponding top portion, as clearly shown in Fig. 7, being helically inclined as mentioned downwardly, in the direction of rotation of the screw fastening members, as will be described later.

20 designates generally the screw spike or fastening member, having the stem 21, provided with the external helical thread, 22. At its upper portion the spike 20 is provided with an approximately circular head, 23, convex on top and bottom, and provided with the non-circular upper head, 24, adapted to be engaged by a wrench, or etc.

A portion of the head, 23, is cut away, as indicated by the numeral, 25, preferably in a plane parallel to the axis of the spike, 20, for a purpose to be hereinafter described.

- 5 The thread, 22, has its inception or initial point, 22^a, as indicated at dotted lines in Fig. 6, at a point in advance of the plane of the cut-off portion, 25, relative to the direction of rotation thereof, *i. e.*, when the 10 screw thread 22 as in the instance shown is a right-handed thread, right-handed rotation will be necessary to screw the same downwardly, when securing in place, when, as shown, point 22^a of the thread will lie 15 forwardly of the cut-off portion, 25, for a reason to be described later.

When assembling my device, the block, 13, is placed upon the tie, 12, and the frame, 15, is super-imposed upon the block, 13, 20 with the spiking apertures or slots 16 in alignment with spiking apertures, 14, in block 13. The rail is located upon the block 13 with its base, 11, between the top portions 15^a, 15^b, of the frame 15, and the entire 25 structure is moved to the desired position, whereupon the spikes, 20, are inserted through the spiking apertures and screwed downwardly there-through into the tie, 12. By locating the thread, 22, with its initial 30 engaging point, 22^a, as shown, I am able when first driving the spike, by placing the cut-off portion 24 with its plane parallel to the vertical axis of the rail-web, to screw the same down to adjacent final position, 35 with the said cut-off portion in position as shown by spike 20^a, Fig. 2. When in this position the head, 23, of the spike, will permit removal or placing of the rail, as will be obvious, and further rotation of the 40 spike in the direction indicated by the arrow in Fig. 2 will operate to bring the spike to its fastening position, as shown by position of spike 20^b, in Fig. 2; although it is not necessary to rotate the same so far over 45 the rail base, unless it is so desired.

The under surface of the head, 23, of the spike, is helically inclined, of a reverse inclination with respect to the thread 22, that is, it corresponds to the inclination of a left- 50 handed thread.

The spike is so constructed and arranged that when in the position of spike 20^b, Fig. 2, contact will take place along the line of the under-side of the spike head, 23, at approximately the beginning point of the dished out portion, 16^a, of the corresponding aperture, 16. This inclined or cut-out portion, 16^a, is preferably in a helical surface similar in inclination to that of the 60 thread 22.

As the rail wears or crushes down upon the block 13, as shown in Fig. 5, the head 24 of the screw spike 20, may be rotated sufficiently to bring the under surface of 65 the head, 23, of the spike again into contact

with the rail flange or base. The inclination of the portion, 16^a, surrounding the aperture, 16, will permit the under surface of the head, 23, to follow downwardly there-along, there being a line contact there-between, thus providing a strengthening or reinforcing means for the head of the spike to resist any thrust imparted thereto by the rail base.

By providing a helical under surface to the head, 23, inclined in a direction opposite to that of the plane of the thread, 22, it will be apparent that all but line contact is eliminated between the under surface of 23 and the metal frame. Furthermore, the under surface of the head, 23, is enabled to ride up over and upon the rail base, and force the same downwardly as the spike is screwed down. This reverse inclination of the under surface of the head operates to enhance the forcing down of the rail base, as will be obvious, so that less rotation of the spike is necessary to maintain the rail-base in position.

If it is desired to remove the rail, all that is necessary is to unscrew the spikes to the position shown by spike 20^a in Fig. 2, when the rail may be removed bodily therefrom without disturbing the location and adjustment of the supporting block and frame, so that when it is desired to replace the rail a uniform gage is maintained, by virtue of the fact that it does not become necessary to remove the rail supporting and fastening means from engagement with the tie. Furthermore, by location of the thread, 22, with its initial point 22^a slightly in advance of the plane of the cut-away portion, 25, of the head 23,—the advance being preferably about a quarter of a turn—all that is necessary when originally placing the spikes is for the workman to place the same with cut away portion 24 parallel with the web of the rail, whereupon he may tap the same with a sledge-hammer into place, and then 105 upon screwing the same down to position as stated above, the head will assume a position shown by spike 20^a in Fig. 2, just previous to contact with the metal frame. This enables the user to get the benefit of the full 110 amount of the adjustment of the spike, as the rail wears down.

While I have shown and described my invention with more or less particularity, I do not wish to be unduly restricted to such 120 showing and description, beyond the scope of the appended claims.

What I claim is:

1. A device of the class described, in combination with a supporting block, a frame member having a top portion resting on said block, said top portion being provided with a spiking aperture, a fastening member adapted to be inserted through said spiking aperture to secure said frame member and 125

supporting block to a tie, or etc., said fastening member being provided with an approximately circular head, partially cut away.

2. A device of the class described, in combination with a supporting block, a frame member having a top portion resting on said block, said top portion being provided with a spiking aperture, a fastening member adapted to be inserted through said spiking aperture to secure said frame member and supporting block to a tie, or etc., said fastening member being provided with an approximately circular head, partially cut away, and said head being provided with a portion adapted to co-act with and rest on said top portion, to prevent outward bending of said head.

3. A device of the class described, in combination with a supporting block, a frame member having a top portion resting on said block, said top portion being provided with a spiking aperture, a fastening member adapted to be inserted through said spiking aperture to secure said frame member and supporting block to a tie, or etc., said fastening member being provided with an approximately circular head, partially cut away, said head being provided with a portion adapted to co-act with and rest on said top portion, to prevent outward bending of said head, and said top portion being dished out and inclined, adjacent said aperture, whereby said head portion of said fastening member will follow and rest on said dished-out inclined portion, as said spike is screwed down.

4. A device of the class described, in com-

bination with a supporting block, a frame member having a top portion resting on said block, said top portion being provided with a spiking aperture, a fastening member adapted to be inserted through said spiking aperture to secure said frame member and supporting block to a tie, or etc., said fastening member being provided with an approximately circular head, partially cut away, said head being provided with a portion adapted to co-act with and rest on said top portion, to prevent outward bending of said head, said top portion being helically dished, with an inclination similar to the helix of said thread of said screw spike.

5. In a device of the class described, the combination of a metal frame, having sides and top portion adapted to partially embrace and rest on said block, said top portions being spaced apart a distance sufficient to permit the mounting of a rail-base on said block therebetween, each of said top portions being provided with a spiking aperture, said top portions being partially dished out to form a helical surface adjacent said spiking aperture, and screw threaded spiking members, adapted to be screwed through said apertures, block, and into a supporting tie, said spiking members each being provided with an approximately circular head having a portion thereof cut away.

In testimony whereof, I have subscribed my name.

DANIEL L. BRAINE.
